(57) **CLAIM**

The ornamental design for a stand for a mobile computing device, as shown and described.

DESCRIPTION

FIG. 1 is a top, front and left side perspective view of the stand for a mobile computing device, showing our new design in an open position;

FIG. 2 is a top, rear and right perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a right side elevational view thereof;

FIG. 8 is a left side elevational view thereof;

FIG. 9 is a top, front and left side perspective view thereof; the view showing the stand for the mobile computing device in a closed position;

FIG. 10 is a top, rear and right side perspective view thereof;

FIG. 11 is a top plan view thereof; and,

FIG. 12 is a bottom plan view thereof.

The broken lines showing portions of the design in the figures are included for the purpose of illustrating environment and unclaimed features and forms not part of the claimed design.

1 Claim, 12 Drawing Sheets
